UNITED STATES PATENT OFFICE.

HENRY BERRY AND KEYES A. HATHAWAY, OF BIRMINGHAM, CONNECTICUT.

DESIGN FOR A LAMP.

SPECIFICATION forming part of Design No. 14,524, dated December 25, 1883.

Application filed November 7, 1883. Term of patent 7 years.

To all whom it may concern:

Be it known that we, HENRY BERRY and KEYES A. HATHAWAY, citizens of the United States, residing at Birmingham, in the county of New Haven and State of Connecticut, have 5 invented a new Design for Lamps; and we do declare the following to be a full, clear, and exact description of the invention, such as will enable others skilled in the art to which it applies to make and use the same, reference being had to the accompanying drawing, and to letters or figures of reference marked thereon, which form a part of this specification.

The figure of the drawing is a representation 10 of a perspective view of the design.

In the drawing is illustrated a lamp. The exposed surface of the lamp at *a* is orna-

mented in conventional imitation of alligator-skin, and this ornamentation is the essential feature of the design, as the bowl may be 20 made of any desired form or size, and with or without handles.

What we claim and desire to secure is—

The design for a lamp having surface ornamentation representing alligator-skin, as 25 shown and described.

In testimony whereof we affix our signatures in presence of two witnesses.

HENRY BERRY.
KEYES A. HATHAWAY.
